8 Claims. (Cl. 262—30)

1

This invention relates to mining machines and more particularly to an improved tilting arrangement for a shortwall coal cutting machine.

During the cutting of coal with a shortwall coal cutting machine there is a tendency of the cutter bar working up or down in the coal due to the unevenness of the mine floor, and it is necessary frequently to jack up or pry up with pinch bars the machine to tilt the same either sideways or endwise to compensate for the unevenness of the floor. Usually, when it is desired to tilt the machine, the latter is jacked up by extraneous floor jacks while the machine remains in a stationary position with respect to the coal face. In certain instances, however, hand operated tilting shoes or skids have been recessed within the bottom of the machine but such shoes or skids are limited in action and due to their relatively small surface area tend to sink into a soft bottom, and their receiving recesses tend to become clogged or jammed with cuttings and dirt rendering them relatively impractical under most mining conditions. It is, however, highly desirable in a shortwall coal cutting machine to provide a built-in tilting arrangement which enables tilting of the machine in any desired direction as the machine is fed over the mine floor during the cutting operation and without the possibility of sinking into a soft bottom or jamming or clogging. Such a tilting arrangement must not increase the height or the overall dimensions of the machine and must not be unduly complicated.

It is an object of the present invention to provide a shortwall coal cutting machine having a built-in tilting arrangement which overcomes the disadvantages of previous devices. Another object is to provide an improved tilting arrangement for a shortwall coal cutting machine which avoids the use of separate shoes or skids recessed within the machine bottom. A further object is to provide an improved skid arrangement which is built into the bottom of the machine whereby the possibility of clogging or jamming as is often encountered in previous devices is avoided. Yet another object is to provide an improved tilting arrangement for a shortwall coal cutting machine wherein the bottom skid of the machine is made separate from the machine frame and tilting devices are arranged between the skid and the frame whereby the frame may be tilted relative to the skid while the latter remains in firm supported contact with the floor of the mine. A still further object is to provide an improved tilting arrangement for a shortwall coal cutting

2

machine wherein the bottom skid and main frame cooperate to provide a cuttings chamber extending through the bottom of the machine through which the cuttings are moved by the cutter chain whereby cuttings discharge occurs at the rear end of the machine remote from the coal face. Another object is to provide an improved tilting arrangement of the fluid operated type whereby the coal cutting machine may be tilted sideways or endwise with comparative ease. A further object is to provide an improved adjustable supporting structure for a coal cutting machine of the floor type. These and other objects and advantages of the invention will, however, herein-after more fully appear.

This application is a continuation of my co-pending application Serial No. 600,299, filed June 19, 1945, now abandoned.

In the accompanying drawings there are shown 20 for purposes of illustration one form and several modifications which the invention may assume in practice.

In these drawings:

Fig. 1 is a plan view of a coal cutting machine 25 with which a preferred illustrative embodiment of the invention is associated.

Fig. 2 is a side elevational view of the coal cutting machine shown in Fig. 1.

Fig. 3 is an enlarged cross-sectional view taken 30 substantially on lines 3—3 of Fig. 2, showing the rear jacks.

Fig. 4 is an enlarged cross-sectional view taken substantially on line 4—4 of Fig. 2, showing the front jacks.

Fig. 5 is an enlarged view in longitudinal vertical section taken substantially on line 5—5 of Fig. 1.

Fig. 6 is a side elevational view showing the machine in tilted position with the cutter bar inclined downwardly.

Fig. 7 is a view similar to Fig. 6, showing the machine in tilted position with the cutter bar inclined upwardly.

Fig. 8 is a front end elevational view of the 45 coal cutting machine, showing the machine tilted about a longitudinal axis with the cutter bar inclined edgewise.

Fig. 9 is a diagrammatical view illustrating the hydraulic system.

Fig. 10 is a detail vertical sectional view, with 50 parts in full, showing a modified arrangement of one of the rear guide sheaves.

Fig. 11 is a detail vertical sectional view, with parts in full, showing a further modified jack construction.

Fig. 12 is a detail horizontal sectional view, with parts in plan, showing a modified mounting for a front guide sheave.

Fig. 13 is a detail vertical sectional view illustrating a modified form of jack mounting.

In this illustrative construction the improved adjustable supporting structure or tilting arrangement is shown associated with a coal cutting machine of the shortwall type which may be generally similar to that disclosed in a patent to Joseph F. Joy et al., Patent No. 2,131,178, patented September 27, 1938. It will be evident, however, that the invention may be embodied in coal cutting machines of other sorts.

The coal cutting machine comprises a machine frame 1 carrying a motor 2, a cutter bar 3 and feeding and controlling drums 4 and 5. The cutter bar is elongated and relatively narrow and projects horizontally lengthwise of the machine frame beneath the latter and has guided thereon an endless cutter chain 6. The cutter bar is suspended beneath the bottom of the machine frame by a hanger 7 preferably formed integral with the frame bottom. The motor 2 has its power shaft connected through spur gears 8, 9 and bevel gears 10, 11 to a vertical shaft 12 suitably journaled within the rearward portion of the machine frame (Fig. 5). The shaft 12 has secured thereto and drives a chain sprocket 13 arranged beneath the machine frame for driving the cutter chain 6. The feeding and controlling drums are arranged at the opposite sides of the machine frame and are connectable in driven relation with the motor through gearing fully described in the above mentioned patent whereby the drums may be independently rotated in winding direction at either low or high speeds under the control of suitable clutches. The feeding and controlling drums 4 and 5 have respectively wound thereon feeding and controlling cables 14 and 15, and journaled on the rear end of the machine frame are pairs of rear guide sheaves 16 and 17 and an intermediate guide sheave 18, while arranged at the forward end of the machine frame are guide sheaves 19, and the cables are adapted to be extended in various manners around these guide sheaves during maneuvering and feeding of the machine as is well understood by those skilled in the art.

Now referring to the improved adjustable supporting structure or tilting arrangement whereby the cutter bar may be tilted about transverse and longitudinal axes to change its angle in altitude, it will be noted that underlying the machine frame is a bottom skid 21 on which the machine frame is supported by a plurality, herein preferably four, of hydraulic power jacks designated 22, 23, 24 and 25 arranged near the four corners of the machine frame and skid. The rear jacks 22 and 23 comprise cylinders 26 mounted in bores 27 formed in projections 28 integral with the machine frame, and flanges 29 are secured as by bolts to the upper surfaces of the projections 28 in the manner shown. The front jacks 24 and 25 each comprise, as shown in Fig. 4, a cylinder 30 arranged beneath the projecting sides of the motor 2 and having upper flanges 31 secured as by screws to the bottom surfaces 32 of the motor projections. The cylinders of the four jacks contain pistons 33 having piston rods 34 extending downwardly through the lower heads 35 of the jack cylinders. These piston rods have secured to their bottom extremities oblate feet 36 seated loosely in sockets 37 formed in socketed members 38 secured to lugs or brack-

ets 39 projecting laterally from the sides of the bottom skid 21. The bottom surfaces of these skid brackets 39 are upwardly and outwardly inclined at 40 to facilitate lateral sliding movement of the skid over the mine floor. If desired the jacks may be mounted in the manner shown in Fig. 13 with the lateral lugs or brackets 39' located near the tops of the sides of the bottom skid, and the jack cylinders in elevated positions at the sides of the machine frame. These four hydraulic jacks 22, 23, 24 and 25 may be operated in such manner as to tilt the machine frame sidewise about a longitudinal axis at either side of the bottom skid or to tilt the machine frame either upwardly or downwardly longitudinally about transverse axes, thereby to change the angle in altitude of the cutter bar as will later be fully explained. The oblate feet 36 loosely received in the sockets 37 of the bottom skid are free to move slightly sidewise to compensate for the tilting of the jacks with the machine frame with respect to the bottom skid. In this improved construction the machine frame has parallel depending flanges or vertical projections 42, 42 along its bottom spaced equidistantly from the longitudinal vertical center of the machine frame as clearly shown in Fig. 4, and these flanges cooperate with and overlap parallel upstanding flanges or projections 43, 43 on the bottom skid with the frame-flanges 43 arranged laterally outside of the skid-flanges 42. These overlapping flanges 42, 43 cooperate with the machine frame and bottom skid to provide a horizontal chamber 44 extending longitudinally through the bottom portion of the machine. The rearward portion of the cutter bar 3 is arranged in this chamber and the cuttings brought back from the kerf by the cutter chain 6 are carried rearwardly through this chamber to discharge at the rear end of the machine remote from the projecting end of the cutter bar. The cooperating flanges 42, 43 on the machine frame and bottom skid are so arranged and constructed that the cuttings are confined in the chamber 44 irrespective of the tilted position of the machine frame with respect to the bottom skid.

Again referring to the guide sheave arrangement, it will be noted that the pairs of rear guide sheaves 16 and 17 are journaled on upstanding axes on the frame projections 28, and the rear jacks 22 and 23 are arranged at the rear corners of the machine frame forwardly of the rearward and inwardly of the outer sheaves of each pair as shown in Fig. 1, and the jacks are desirably located rearwardly of the feeding and controlling drums 4 and 5. The front guide sheaves 19 are herein mounted on swing arms 46 which straddle the front jacks 24 and 25 and have spaced lugs 47 pivotally mounted on bolts 48 supported by lugs 49 integral with the machine frame. Thus, the swing arms 46 may swing in a vertical direction about axes extending longitudinally of the machine frame to vary the angle of the front guide sheaves. By arranging the swing arms so that they straddle the front jacks, it is possible to locate these jacks near the front corners of the machine frame in the manner shown. The sheaves 19 are preferably arranged in an inclined position so that the cables may be extended forwardly from the bottoms of the drums around these sheaves as desired. In the modification shown in Fig. 10, one of each pair of rear sheaves 16 and 17 surrounds the cylinder 28' of each of the rear jacks. Each

jack cylinder supports a bearing 51 on which the sheave is journaled, and a collar 52 secured by a set screw 53 to the upper portion of the jack cylinder retains the guide sheave in position at the upper surface of the frame projection 28'. By arranging certain of the guide sheaves coaxial with the jack cylinders, extreme simplicity and compactness are attained. In like manner, the front guide sheaves 19 may be mounted in coaxial relation with the cylinders of the front jacks, although with such an arrangement, the pivoted swing arm mounting for the sheaves must be omitted. In the modification shown in Fig. 11, conventional hand operated jacks 55 have been substituted for the four-power jacks at the four corners of the machine frame, and these hand jacks are inverted and rest on the bottom skid 21. The jack pistons have piston rods 56 extending upwardly through the top cylinder heads 57 and the upper ends of the piston rods have oblate portions 58 loosely arranged in a socketed member 59 attached to a lug 60 integral with the machine frame. Each hand jack has a conventional built-in pump 61 operated by a hand lever 62. In the modification shown in Fig. 12, the front guide sheave 19 is mounted on a horizontally swingable arm 63 pivotally mounted at 64 on the cylinders of the front jacks 24, 25. When these sheaves are in the full line position shown in Fig. 12, lugs 65 on the arms engage the inner sides of the machine frame so that the sheaves are firmly held in the position shown by the feeding pull on the feeding cable. When the swing arm is swung horizontally forwardly, it assumes the dotted line position shown in Fig. 12 with the swing arm against the side of the machine frame.

Now referring to the hydraulic system for supplying liquid under pressure to the cylinders of the power jacks 22, 23, 24 and 25, it will be noted that arranged within the frame of the machine is a conventional pump 67 having its power shaft 68 driven by a spur gear 69 meshing with the motor shaft gear 8. The pump 67 is preferably arranged within a liquid tank 70 having a suitable filler plug 71. As shown diagrammatically in Fig. 9, the pump has its intake conduit 72 connected to the tank 70, and the pump discharge conduit 73 is connected to the supply passage of a valve box 74 herein conveniently located at the rear end of the machine frame. The pressure conduit 73 is connectible through a relief valve 75 and conduit 76 back to the tank 70. The exhaust passage of the valve box 74 is connected through a return conduit 77 back to the tank. The valve box 74 has bores containing four conventional slide valves 78, 79, 80 and 81 (shown diagrammatically in Fig. 9) provided with operating levers 82. The valve box is connected through conduits 83, 84, 85 and 86 to the upper ends of the cylinders of the four hydraulic jacks. By suitably manipulating the levers for the valves 78, 79, 80 and 81, liquid under pressure may be supplied to the jack cylinders as desired either in pairs or concurrently so that the pairs of side jacks may be selectively operated to tilt the machine frame in one direction or the other about a longitudinal axis, or the pairs of end jacks may be selectively operated to tilt the machine frame in either direction about a transverse axis as desired. By operating the four jacks concurrently the machine frame may be elevated while the cutter bar is maintained in substantially horizontal position.

The general mode of operation of the improved

coal cutting machine is as follows: The feeding and controlling cables 14 and 15 may be extended from their respective drums around certain of the guide sheaves as shown in Fig. 1, and laterally from the machine to suitable anchor jacks located at the ribs of the mine room. The drums may be operated and controlled in the manner fully described in the patent above referred to so that the cutter bar may be dumped beneath the coal at one rib, then fed transversely across the coal face, and thereafter withdrawn from the face at the opposite rib all in the manner well known to those skilled in the art. By reversing the motor, rewinding the cables on the drums, reversing the pump connections, and reversing the cutter bits on the cutter chain, the machine may operate in the reverse direction. During either direction of cutting, the slide valves 78, 79, 80 and 81 controlling the hydraulic power jacks 22, 23, 24 and 25 may be operated to effect tilting of the machine frame about transverse and longitudinal axes to vary the angle in altitude of the cutter bar, thereby to facilitate the cutting functions. For example, two of the jacks 20 at one side of the machine frame may be concurrently operated to tilt the machine frame about a longitudinal axis at the opposite side of the skid and, in like manner, the two jacks at the opposite side of the machine frame may be concurrently operated to tilt the machine frame about a longitudinal axis in the opposite direction. Thus, the cutter bar may be tilted in either direction about parallel longitudinal axes to effect edgewise tilting of the cutter bar as shown in Fig. 7. The pair of jacks at the rear end of the machine frame may be concurrently operated to raise the rear end of the machine frame to tilt the cutter bar about a transverse axis located at the front end of the bottom skid to tilt the cutter bar downwardly as shown in Fig. 6. The front jacks may be concurrently operated to raise the front end of the machine frame to tilt the cutter bar upwardly, as shown in Fig. 7, about a transverse axis located at the rear end of the bottom skid. And all four jacks may be concurrently operated to elevate the machine frame to locate the cutter bar in a horizontal position some distance above the floor level. When hand operated hydraulic jacks such as shown in Fig. 11 are employed instead of the power jacks, tilting of the machine may be effected as desired simply by operating the pumps of the jacks either separately or in pairs in an obvious manner.

As a result of this invention, an improved adjustable supporting structure or tilting arrangement is provided for a standard shortwall coal cutter whereby, without raising the machine bottom from the mine floor, the machine frame 45 may be tilted about transverse and longitudinal axes to change the angle in altitude of the cutter bar. By building the hydraulic jack mechanism into a standard shortwall coal cutting machine, the cutter bar may be tilted at will about transverse and longitudinal axes while the cuttings brought back from the kerf by the cutter chain are moved through the bottom of the machine to discharge at the rear end of the machine. By incorporating the jack mechanism within the bottom skid structure of a shortwall machine, it is possible to tilt the cutter bar without the use of extraneous jacks or skids. The improved adjustable skid mounting for a standard shortwall coal cutting machine enables the cutter bar to be tilted as desired without inter-

rupting the feeding movement of the machine and while the cuttings are moved by the cutter chain through the bottom of the machine to discharge at the rear end of the machine irrespective of the tilted position of the cutter bar. The improved skid structure eliminates the need of separate tilting shoes recessed within the machine bottom as in previous known devices so that sinking into a soft bottom and the clogging of the skids and shoes, due to dirt and cuttings getting into their receiving recesses, is avoided. By the provision of the improved built-in, power operated jack structure for a standard shortwall floor cutter, the tedious and time-consuming task of jacking up the machine at frequent intervals during the cutting operation by means of extraneous jack devices or pinch bars is wholly avoided, a decided advantage in mines having low headroom. Other uses and advantages of the improved adjustable supporting structure or tilting arrangement will be clearly apparent to those skilled in the art.

While there are in this application specifically described one form and several modifications which the invention may assume in practice, it will be understood that this form and several modifications of the same are shown for purposes of illustration and that the invention may be further modified and embodied in various other forms without departing from its spirit or the scope of the appended claims.

What I claim as new and desire to secure by Letters Patent is:

1. In a shortwall coal cutting machine of the floor type, a bottom skid slidable over the floor of a mine and constituting the machine bottom, a machine frame mounted on said skid in overlying relation with respect thereto and having a horizontal open bottom in substantial parallelism with the skid bottom when said frame is in lowered position on said skid, said skid and said frame having cooperating side portions arranged in overlapping relation, a horizontal plane cutter bar secured to the frame bottom and projecting horizontally from said frame lengthwise thereof above the skid bottom when said frame bottom and said skid are in parallelism, a cutter chain guided for circulation about the margin of said cutter bar, said skid and the lower portion of said machine frame in all adjusted positions of the latter with respect to said skid cooperating to provide a horizontal chamber between said skid and the bottom of said frame just above the floor level and in which the rearward portion of said cutter chain is arranged, said cutter chain as it circulates during the kerf cutting operation moving the cuttings created thereby rearwardly in said chamber to discharge near the floor level at the rear end of the machine, said skid and said frame with their cooperating and overlapping side portions confining said cuttings in said chamber as they are moved longitudinally rearwardly therethrough irrespective of the tilted position of said frame with respect to said skid, and means for pivotally mounting said frame on said skid and for tilting said frame and said cutter bar about a generally horizontal axis comprising extensible tilting devices arranged between said skid and said frame for exerting on the latter an upwardly directed force for tilting said frame and said cutter bar in a vertical direction about said axis relative to said skid to change the angle of the cutter bar with respect to the horizontal.

2. In a shortwall coal cutting machine of the floor type, the combination comprising a bottom

skid slidable over the floor of a mine and constituting the machine bottom, a machine frame overlying said skid and having a horizontal open bottom spaced above the skid bottom in substantial parallelism therewith when said frame is in lowered position on said skid, an elongated horizontal plane cutter bar supported by said machine frame and rigidly secured to said frame bottom and extending horizontally lengthwise thereof below the bottom of said frame in the space between the latter and the skid bottom when said frame and said skid are in parallelism, a cutter chain guided for circulation about the margin of said cutter bar for cutting a horizontal kerf substantially at the floor level and for moving the cuttings created thereby during the cutting operation rearwardly in the space between the frame bottom and the skid bottom to discharge near the floor level at the rear end of the machine, and adjustable supporting mechanism between said skid and said machine frame for supporting the latter above the skid bottom and for tilting said frame and said cutter bar about a generally horizontal axis comprising adjustable tilting devices arranged between said skid and said frame for exerting on the latter an upwardly directed force for tilting said frame and said cutter bar in a vertical direction about said axis relative to said skid to change the angle of the cutter bar with respect to the horizontal, said bottom skid and said machine frame having cooperating side closure portions whereby the cuttings are confined in the space therebetween during the movement of the cuttings rearwardly therethrough to discharge at the rear end of the machine irrespective of the tilted position of the machine frame with respect to the bottom skid.

3. A coal mining machine comprising, in combination, a bottom skid, a machine frame mounted on and overlying said skid, adjustable jack devices connected between said skid and said frame for tilting the latter relative to said skid, a cutter bar secured to the bottom of said frame and projecting forwardly from said frame, said skid and said frame having side closure portions cooperating to provide side closures thereby to form a substantially closed wall chamber extending lengthwise through the bottom of the machine and in which the rearward portion of said cutter bar is arranged, an endless cutter chain guided for circulation in an orbital path about the margin of said cutter bar, and a motor carried by said tiltable frame for driving said cutter chain, said cooperating portions of said skid and said frame providing said side closures for said chamber irrespective of the tilted position of said frame relative to said skid whereby said cutter chain may move the cuttings created during the cutting operation rearwardly through said chamber to discharge at the rear end of the machine, and means for adjusting said jack devices to exert upwardly directed forces on said frame to tilt the latter relative to said skid to vary the inclination of said cutter bar with respect to the horizontal.

4. In a coal mining machine, the combination comprising a bottom skid slidable over the floor of a mine, a machine frame overlying and mounted on said skid, a cutter bar secured to the bottom of said frame between the latter and said skid and extending forwardly lengthwise of the machine, an endless cutter chain guided for circulation about the margin of said cutter bar, a motor carried by said frame for driving said cutter chain to move the latter in an orbital path,

said skid and said frame having side portions cooperating with the bottoms of said skid and frame to provide a chamber extending lengthwise throughout the bottom of the machine and in which said cutter chain moves orbitally to convey the cuttings created during the cutting operation rearwardly through said chamber to discharge at the rear end of the machine, and four independently operable hydraulic jacks arranged at the four corners of said frame between the latter and said skid for exerting upwardly directed forces on said frame to tilt said frame relative to said skid to vary the inclination of said cutter bar with respect to the horizontal, and said cooperating portions of said skid and said frame retaining the cuttings in said chamber during movement of the cuttings lengthwise through said chamber irrespective of the tilted position of said frame relative to said skid.

5. In a shortwall coal cutting machine of the floor type, a bottom skid slideable over the floor of a mine and constituting the machine bottom, a machine frame mounted on said skid in overlying relation with respect thereto and having a horizontal open bottom in substantial parallelism with the skid bottom when said frame is in lowered horizontal position on said skid, a horizontal plane cutter bar secured to the frame bottom and projecting horizontally from said frame lengthwise thereof above the skid bottom close to the latter when said frame is in said lowered horizontal position, a cutter chain guided for circulation in an orbital path about the margin of said cutter bar for cutting a horizontal kerf near the floor level, said skid and the lower portion of said machine frame having side closure portions which cooperate in all adjusted positions of said frame with respect to said skid to provide a substantially closed wall horizontal chamber extending lengthwise of the machine between said skid and the frame bottom just above the floor level and in which the rearward portion of said cutter chain is arranged, said cutter chain as it circulates during the kerf cutting operation moving the cuttings created thereby rearwardly in said chamber to discharge near the floor level at the rear end of the machine, and means for pivotally mounting said frame on said skid and for tilting said frame and said cutter bar about a generally horizontal axis comprising extensible tilting devices arranged between said skid and said frame for exerting on the latter upwardly directed forces for tilting said frame and said cutter bar in a vertical direction about said axis relative to said skid to change the angle of the bar with respect to the horizontal.

6. In a coal mining machine, a bottom skid slideable on its bottom over the floor of a mine, a machine frame overlying and mounted on said skid, a horizontal plane cutter bar secured to the bottom of said frame with its forward portion extending forwardly lengthwise of the machine, the rearward portion of said cutter bar arranged between said frame bottom and the bottom of said skid, said frame and skid having side closure portions cooperating to provide side closures thereby to form a longitudinal substantially closed wall chamber between said skid and said frame and in which the rearward portion of said cutter bar is arranged, a cutter chain guided for circulation in an orbital path about the margin of said cutter bar for moving the cuttings created during the cutting operation rearwardly through said chamber to discharge at the rear end of the machine, a motor carried by said frame for driv-

10 ing said cutter chain, four hydraulic jacks one at each of the four corners of the machine frame and arranged between said skid and said frame for exerting upwardly directed forces on said frame to tilt the latter relative to said skid to vary the inclination of said cutter bar with respect to the horizontal, said cooperating portions of said skid and said frame providing said side closures for said chamber irrespective of the tilted position of said frame relative to said skid whereby the cuttings are confined for rearward movement within said chamber to discharge at the rear end of the machine, a pump on said frame and driven by said motor, a liquid reservoir on said frame with which the suction side of said pump is connected, control valve means connected to the discharge side of said pump and including control valves, one individual to each jack, whereby flow of liquid under pressure to the jacks may be independently controlled, said valves being positionable to trap liquid in said jacks to lock said jacks in adjusted position; and means for connecting the discharge passage of said valve means back to said reservoir.

25 7. In a shortwall coal cutting machine of the type slideable on its bottom over the floor of a mine during its operation, the combination comprising a bottom skid constituting the machine bottom, a machine frame mounted on said skid in overlying relation with respect thereto and having a horizontal open bottom in substantial parallelism with the skid bottom when said frame is in lowered horizontal position on said skid, a horizontal plane cutter bar secured to the frame bottom and projecting horizontally from said frame lengthwise thereof above the skid bottom close to the latter when said frame is in said lowered horizontal position, a cutter chain guided for circulation in an orbital path about the margin of said cutter bar for cutting a horizontal kerf near the floor level, said skid and said frame having side wall portions cooperating in all adjusted positions of said frame with respect to said skid to provide a horizontal substantially closed wall chamber extending lengthwise of the machine between said skid bottom and said frame bottom just above the floor level and in which the rearward portion of said cutter chain is arranged, said cutter chain as it circulates during the cutting operation moving the cuttings created thereby rearwardly in said chamber to discharge near the floor level at the rear end of the machine, and four hydraulic jacks one arranged at each corner of the machine frame and connected between said skid and said frame for pivotally mounting the latter on said skid and for exerting upwardly directed forces on said frame to tilt said frame to change the inclination of said cutter bar with respect to the horizontal, said hydraulic jacks being positioned at the outer sides of said skid and frame with said chamber extending longitudinally between the side jacks, and means for operating said jacks to exert upwardly directed forces on said frame for tilting said frame in a vertical direction about a horizontal axis relative to said skid.

70 8. In a shortwall coal cutting machine, the combination comprising a skid slideable on its bottom over the floor of a mine, a machine frame overlying and mounted on said skid with its bottom spaced from the skid bottom above the latter, a horizontal plane kerf cutter secured to the bottom of said frame and extending lengthwise of the machine in the space between the frame bottom and the bottom of said skid for cutting a

11

horizontal kerf near the floor level, said kerf cutter having its rearward portion disposed at the rearward end of said frame and its forward portion projecting forwardly from the front end of said frame whereby the cuttings created during the cutting operation are moved rearwardly from the kerf through the space between the frame bottom and the bottom of said skid to discharge rearwardly from the rear end of the machine, said skid and said frame having cooperating side wall portions to provide an enclosure at the sides of said space so that the cuttings conveyed rearwardly by said kerf cutter are confined in said space and conveyed rearwardly therein to discharge at the rear end of the machine, four hydraulic jacks, one disposed at each corner of said frame and arranged between said skid and said frame for exerting upwardly directed forces on said frame selectively at different points whereby said frame may be tilted either sidewise or endwise relative to said skid to vary the inclination of said kerf cutter with respect to the horizontal, said jacks being arranged at the sides of the machine laterally outside of the enclosed space in which the cuttings are moved rearwardly by the kerf cutter with the rear jacks so located that the cuttings are discharged freely rearwardly from the machine, and means for independently controlling operation of said jacks whereby the two front jacks may be

5 operated to tilt said frame to incline said kerf cutter upwardly, the two rear jacks may be operated to tilt said frame to incline said kerf cutter downwardly, or the pair of jacks at either side of the machine may be operated to tilt said frame to incline said kerf cutter sidewise about a longitudinal axis.
